UNITED STATES PATENT OFFICE.

JOSEPH GELE, OF NEW YORK, N. Y.

ELECTRIC-ARC LAMP.

1,272,418.

Specification of Letters Patent. Patented July 16, 1918.

Application filed June 29, 1916. Serial No. 106,602.

To all whom it may concern:

Be it known that I, JOSEPH GELE, a subject of the Emperor of Austria, residing in the borough of Bronx, county of Bronx, 5 and State of New York, have invented certain new and useful Improvements in Electric-Arc Lamps, of which the following is a specification.

This invention aims to provide certain 10 improvements in arc lamps especially designed for photographic work or for projecting work, as in the taking and projecting of moving pictures but applicable also to other uses.

15 The accompanying drawings illustrate a lamp embodying the invention.

Figure 1 is a front elevation of the complete lamp, partly broken away;

20 Fig. 2 is a longitudinal section through the clutches and adjacent parts;

Fig. 3 is a horizontal section on the line 3—3 of Fig. 1;

Fig. 4 is a separate detail of Fig. 3;

25 Fig. 5 is a transverse section on the line 5—5 of Fig. 3;

Figs. 6 and 7 are horizontal sections on the lines 6—6 and 7—7 respectively of Fig. 1, looking in the directions of the arrows;

30 Fig. 8 is a transverse view approximately on the line 8—8 of Fig. 2;

Fig. 9 is a detail illustrating a spring connection in the clutch rods, the view being on the line 9—9 of Fig. 2.

Referring now to the embodiments of the 35 invention illustrated there are a fixed electrode A and movable electrodes B and B'. The fixed electrode is supported in a clamp C by means of a set screw D, the clamp C being threaded on a screw E on the forward 40 end of a bracket F which is fastened to a fixed cross bar G mounted on a frame comprising longitudinally extending rods H connected to each other by intermediate fixed cross bars J and end cross bars K.

45 The fixed electrode A can be adjusted transversely inward or outward by the screw E and fastened in place by the set screw L. The movable electrodes B and B' are mounted in similar clamps C carried on brackets 50 F and adjustable transversely toward and from the frame comprising the rods H and connecting cross bars. The clamps C can be turned about the screws E as a center and thus permit a radial adjustment of the

electrodes. The brackets F for the movable 55 electrodes are connected to cross bars M and M' which are mounted to slide on the rods H so as to move the electrodes B and B' toward and away from the fixed electrodes. Binding screws N and N' are mounted on 60 the brackets which carry the movable electrodes for attachments of the wires O and O', Fig. 1. The current passes from the binding screw N through the electrodes B, 65 A and B' in turn to the binding screw N'. 5

The frame consisting of the rods H and cross bars is suspended by posts P below a plate Q which in turn is suspended by rods R from the head S of the lamp, which head also carried the solenoid T and coil U which 70 control the feeding of the carbons and the regulation of the arc. The plate Q carries binding posts V and V' which are connected to the wires O and O' and also to wires W and W' running through the coils above in 75 the usual way to the line.

The cross bar M is connected by an upright X to a rack Y which slides longitudinally along the underside of the plate Q and is actuated by a pinion Z at the right 80 hand side of the machine; while the cross bar M' which carries the movable electrode B' is similarly connected by an upright X' to a rack Y' sliding beneath the plate Q and actuated by a pinion Z' at the left of the 85 machine. The overlapping arrangement of the racks Y and Y' is indicated in Figs. 6 and 7. The weight of the electrodes and brackets is carried, through the cross bars M and M', on the rods H, on which they 90 slide freely, and the engagement of the racks and pinions is not a supporting engagement but merely a driving one. The upright X has a vertically adjustable connection with the sliding cross bar M, as shown in Fig. 5, 95 to adjust the rack above in proper engagement with its pinion, and the upright X' is similarly mounted. The pinions Z and Z' are freely supported on pivots in brackets 2 depending from the plate Q.

100 The pinion Z is actuated by means of a vertical rack bar 3 which extends upward through the plate Q and carries on its upper end a weight comprising a cross bar 4 having its ends arranged to slide on the rods R. The pinion Z' is similarly actuated by a vertical rack bar 3a having a weight 4a at 105 its upper end. The weights, therefore, turn

the pinions in the directions indicated by the arrows and these in turn slide the racks and the movable electrodes toward each other.

Depending from the weights 4 and 4^a are 5 clutch-operated rods 5 and 5^a which are automatically lifted, carrying the racks with them, when the electrodes are to be separated. These clutch-operated rods pass through clutches 6 and 6^a of a known type 10 which are operated by rods 7 and 7^a connected at their upper ends to a cross head 8 which is pivotally mounted in the usual way on the solenoid core 9, the lower end of which is connected to the cylinder 10 15 of a dashpot, the piston rod 11 of which is fixed to a cross bar 12 supported by rods 13 from overhead. The clutch operating rod 7 (and 7^a similarly) has a yielding spring connection 14 (Fig. 9) at an intermediate 20 point of its length.

When there is no current the solenoid core falls so that the lower leaves of the clutches 6 and 6^a strike on the plate Q and the 25 clutches release the rods 7 and 7^a, allowing the weights 4 and 4^a and their rack bars to fall until the electrodes are brought into contact with each other, each of the movable electrodes moving independently of the other. If now the circuit of the lamp be 30 closed the solenoid works in the usual way to pull up its core at a rate moderated by the dashpot. The clutches are brought into engagement with the rods 5 and 5^a. The latter are then lifted and the electrodes separated slowly until the determined length 35 of arc is struck, the solenoid holding the parts in this position. As the electrodes burn and the arcs lengthen the solenoid lowers the clutches and releases the weighted 40 rods 5 and 5^a so as to cause the electrodes to move toward each other and shorten the arcs.

The same arrangement may be applied to a lamp with a single arc, this being especially 45 useful for projecting apparatus, either by using only one movable electrode and one-half of the operating mechanism, or by omitting the intermediate fixed electrode and using the two movable electrodes with 50 the double operating mechanism shown. Or a greater distribution of light may be secured, as is desirable in taking pictures, by increasing the number of arcs; as for example by mounting an additional set of electrodes 55 in the brackets C (Fig. 1), below the electrodes shown, for four arcs, or by mounting two additional sets of electrodes in a similar way for six arcs. The same mechanism may be used for operating electrodes 60 in inclined or other non-vertical directions; the rack and pinion mechanism or chain mechanism or other equivalent means being useful wherever a change of direction is necessary and regardless of the style of magnet or other motor device used.

Though I have described with great particularity of detail a certain embodiment of my invention yet it is not to be understood therefrom that the invention is restricted to the particular construction illustrated and 70 described. Various other constructions may be designed by those skilled in the art without departing from the invention as defined in the following claims.

What I claim is—

1. An electric arc lamp including in combination a clutch, a vertical rack actuated by gravity in one direction and magnetically in the opposite direction to maintain the length of the arc, a horizontal electrode, a clamp for holding the same, a bracket connected at its outer end with said clamp, means for adjusting said clamp toward and away from said bracket, movable cross-bars connected to the inner end of 80 said bracket, longitudinally extending rods adapted for engagement with and upon which said cross-bars are slidable and a horizontal rack to shift said electrode. 85

2. An electric arc lamp including in combination supporting means, horizontal electrodes located in a vertical plane in front of and below said supporting means, brackets and transversely adjustable clamps for holding said electrodes, means for shifting said 90 brackets and clamps horizontally on said supporting means and means for maintaining an arc between said electrodes.

3. An electric arc lamp including in combination supporting means, a stationary 100 horizontal electrode, a bracket and a transversely adjustable clamp for supporting said electrode, a plurality of movable horizontal electrodes, longitudinally adjustable brackets and transversely adjustable supporting 105 means carried by said brackets for the movable electrodes, and means carried by the above mentioned supporting means for shifting said movable electrodes for maintaining arcs between said movable and said 110 stationary electrodes.

4. An electric arc lamp including in combination a stationary electrode, a plurality of movable electrodes, clutches to control the operation of said movable electrodes, gravity operated means for independently operating each movable electrode in one direction, and a single magnetic means for operating said electrodes in the opposite direction, and compensating means between said 115 magnetic means and said clutches for maintaining arcs of equal length between the electrodes. 120

5. An electric arc lamp including in combination supporting means, a stationary 125 electrode, a bracket carried by said supporting means, a radially and transversely adjustable clamp carried by said bracket for the stationary electrode, a plurality of movable electrodes, slidable brackets and 130

radially and transversely adjustable clamps carried by said slidable brackets for the movable electrodes, means for shifting each of said slidable brackets independently in 5 one direction, magnetic means for shifting the movable brackets and electrodes, clutches to control the shifting of said brackets and electrodes and a compensating device between said clutches and said magnetic means to maintain arcs of equal length between 10 the electrodes.

In witness whereof, I have hereunto signed my name.

JOSEPH GELB.
